Primary Examiner — Bao-Yen T Nguyen*Assistant Examiner* — Amanda J Berlinski(74) *Attorney, Agent, or Firm* — McDonnell Boehnen Hulbert & Berghoff LLP(57) **CLAIM**

We claim the ornamental design for an injection device, as shown and described.

DESCRIPTION

FIG. 1 is a perspective view of the back, right and top of the injection device;

FIG. 2 is a perspective view of the front, right and side thereof;

FIG. 3 is a top plan view thereof;

FIG. 4 is a bottom plan view thereof;

FIG. 5 is a right side elevation view thereof;

FIG. 6 is a left side elevation thereof;

FIG. 7 is a front elevation view thereof; and,

FIG. 8 is a back elevation view thereof.

The broken lines in the drawings illustrate portions of the injection device that form no part of the claimed design.

1 Claim, 5 Drawing Sheets(56)
